MULTISTAGE COMPRESSOR.

1,194,687.

Specification of Letters Patent. Patented Aug. 15, 1916.

Application filed September 8, 1910. Serial No. 580,971.

To all whom it may concern:

Be it known that I, GEORGE WESTINGHOUSE, a citizen of the United States, and a resident of Pittsburgh, in the county of Allegheny and State of Pennsylvania, have made a new and useful Invention in Multistage Compressors, of which the following is a specification.

This invention relates to compressors and has for an object to produce a new, improved and compact multistage or compound compressor.

A further object is to produce a compressor adapted to be employed in connection with the compression system of an internal combustion engine.

A further object is to produce a compressor for compressing the air component of the charge for an internal combustion engine, and also to produce means for introducing fuel into the air after it is compressed.

A further object is to produce a compressor, in which means are employed for discharging the compressed air into the distributing system of an internal combustion engine and into a storage tank or reservoir; or for discharging the compressed air, either into the tank or distributing system.

These and other objects I attain in a compressor embodying the features herein described, and illustrated in the drawings accompanying this application and forming a part thereof.

In the drawings: Figure 1 is a vertical section of a compressor embodying my invention; Fig. 2 is a fragmental plan view of the lower portion of the compressor casing, a portion being shown broken away and in section for convenience of illustration; and Fig. 3 is a fragmental sectional view corresponding to the section of Fig. 1 and illustrates the arrangement of the discharge valve of the compressor on an enlarged scale.

Referring to the drawings: The compressor illustrated, as an embodiment of my invention, consists of a cylindrical casing formed in two parts 4 and 5, and a compound piston located within the casing and reciprocated by means of a connecting rod 6. The lower portion 5 of the casing is bored to two diameters, the cylindrical chamber 7 formed by the larger bore, being lo-

cated in the upper portion of the part 5, in communication with the air inlet ports of 55 the compressor. The upper part 4 of the casing is bored so as to form a single compression chamber 8 and is secured in place on the part 5 by any suitable means, such as bolts 9, so as to close the upper end of the 80 chamber 7.

The compound piston consists of a hollow piston 11, adapted to operate in the chamber 8 to finally compress the air, a piston 12 integrally formed with the piston 11 and 65 adapted to operate in the chamber 7, and a trunk piston 13, on which the pistons 11 and 12 are mounted. The piston 13 is of smaller diameter than the piston 12 and is adapted to operate in the smaller bore of the lower 70 part 5 of the casing.

A passage 14 is formed within the walls of the lower part 5 of the casing and communicates with an air inlet port 15, formed in the casing, and a series of inlet ports 16, 75 arranged in an annular row around the casing. The ports 16 communicate with the chamber 7 and are controlled by a ring shaped valve 17, which seats, by its own weight, to close the ports, and is held firmly 80 against its seat by the pressure within the chamber 7 during the compression stroke of the piston 12.

During the downward stroke of the compound piston of the compressor, the valve 17 85 is unseated by the external pressure of the air, and the chamber 7 is filled with air. During the upward stroke of the piston, the valve 17 seats to close the ports 16 and is firmly held on its seat by the increasing fluid 90 pressure within the chamber 7, as has been stated. The air confined in the chamber is forced, through an annular row of ports 18 formed in the piston 12, into an annular space segregated from the chamber 95 7 by the compound piston, and located between the cylindrical wall of the chamber 7, the cylindrical wall of the trunk piston 13, the lower side of the piston 12 and a shoulder 19, formed on the lower 100 part 5 of the casing by the difference in diameters between the bores.

The ports 18 are controlled by a ring shaped valve 21, which is adapted to be held in its closed position on the piston 12 by 105 the preponderance of pressure in the segre-

gated portion of the chamber 7, and which seats on the upper edge of the trunk piston 13 when in the open position. When the ports 18 are open, they communicate with 5 an annular series of passages 22 formed in an annular projection 23 of the trunk piston 13.

The passages 22 may be drilled in the projection 23 and they communicate with 10 a chamber 24 located within the piston 11. A ring shaped valve 25 is located on the projection 23 and controls the delivery through the passages 22. The valve is 15 adapted to seat by its own weight and is held in the closed position by the pressure in the chamber 24.

The chamber 24 communicates with the chamber 8 through a port 26, which is controlled by a puppet valve 27 carried by the 20 piston 11 and operating as a check valve between the chamber 24 and the chamber 8. The chamber 8 is shown lined with a brass bushing 29, and a discharge valve 30 is mounted on the upper end of the bushing 25 and controls a discharge port 31 formed in the bushing. The discharge port communicates, through a suitable discharge passage, with a chamber 32 formed in a cap portion 33, which is bolted to the casing, and 30 the chamber 32 may communicate with a compressed air distributing system through pipe 34.

A recess 35 is formed in the casing and is adapted to communicate with a pressure 35 storing tank (not shown) through piping 36. The recess 35 communicates with the port 31 through a passage 37, which is controlled by the valve 30. A passage 38 is also formed in the casing and communicates 40 with the recess 35 and an annular passage 39 formed in a screw plug 40, which holds the upper end of the bushing in place. The passage 39 communicates with the discharge passage above the valve 30 and is controlled by a ring shaped valve 41, which is held to its seat, so as to close the recess 39, by the pressure within the discharge passage. The valve 30 is held to its seat on the bushing 29 by means of an adjustable coiled 50 spring 42, which surrounds the stem of the valve.

The piston 12 is provided with a suitable piston ring 43, which is located in an annular recess formed in the cylindrical wall 55 of the piston and is adapted to engage the cylindrical wall of the chamber 7. The piston 13 is provided with a similar packing ring 44, which is located in a recess formed in the lower end of the piston and is adapted to engage the cylindrical wall of the smaller bore of the part 5. Any suitable form of packing rings may be employed. A series of packing rings 45 surround the piston 11 and are located in a recess formed 60 concentrically with the bore of the chamber

8. The packing rings are held in place by means of an annular screw plug, which surrounds the piston 11 and is adapted to be screwed into the part 4 of the casing.

I find it convenient to introduce the lubricant for the compressor into the air entering the inlet port 15. In this way, I am able to lubricate all the working surface of the compressor, and at the same time provide means for maintaining the packings 70 air tight. The air entering the chamber 7 will carry lubricant with it, which will lubricate the cylindrical wall of that chamber and which will pass with the air into the segregated space around the trunk piston and also into the chamber 8. The lubricant will be wiped off of the cylindrical walls of the lower part 5 of the casing by the packings 43 and 44; and by collecting in the packings, will aid in rendering them air 75 tight. As the piston 11 reciprocates through the chamber 7 and also through the chamber 8, it will convey lubricant to the rings 45 and this lubricant will aid in packing the joint between the chambers 7 and 8. In 80 case it is objectionable to introduce the lubricant into the air, other ordinary means may be employed for lubricating the piston of the compressor.

The casing of the compressor is so formed 85 that it provides a water jacket from the chambers 7 and 8. The jacket for the chamber 7 is formed within the walls of the part 5 of the casing and it almost entirely surrounds the chamber; the air passage 14, 10: however, replaces a portion of the water jacket and extends around the upper portion of the chamber 7. A passage 46 is formed within the walls of the casing, between the ends of the passage 14, and provides a means of communication between the jacket space of the lower part and the jacket space of the upper part of the casing. Holes 47 are drilled through the part 5 of the casing so that they communicate with 10: the passage 46 and holes 48 and are drilled in the upper part of the casing and are so located that they communicate with the jacket space of the upper part 4 and registered with the holes 47 when the part 4 is secured in place on the part 5.

Cooling water is introduced into the jacket space through a pipe 49, which communicates with the lowest point of the jacket space of the part 5; and cooling water is 12: discharged from the upper part of the jacket space in the part 4 by means of a pipe 51. The jacket space of the upper part 4 is prevented from surrounding the chamber 8 by the inter-position of a plunger cylinder 12: 52, which communicates with a source of liquid fuel supply through a port 53 located near the top of the cylinder and suitable piping 54. The cylinder 52 is bored out of the upper part 4 of the casing and is shown 12:

as lined with a brass bushing 55, which is secured in place, as hereinafter described.

A plunger 56 is secured to the piston 12 of the compressor and operates in the cylinder 52 to compress the liquid fuel delivered through the port 53, and to deliver it under pressure to the discharge passages of the compressor. The upper end of the cylinder 52 is provided with a port 57, which communicates with the discharge passages of the compressor through a passage 58 and an annular recess 59, which surrounds the valve 30. The port 57 is also controlled by a ball check valve 61, which is held to its seat with considerable force by means of a coiled spring 62 operating between the valve and a screw plug 63 screwed into the casing of the compressor and adapted to hold the bushing 55 in place. The lower end of the bushing 55 is held in place by means of packing rings 64, which surround the plunger 56 and which are held in place by a screw plug 65, threaded into the part 4 of the casing. The lubricant wiped off of the plunger 56 by the rings 64 will operate to aid the ring in maintaining an air tight joint between the chamber 7 and the cylinder 52. It will be apparent that the cylinder 52, plunger 56 and the discharge passage 58, 30 may be so arranged that the compressed liquid fuel will be delivered into the engine cylinders, instead of the discharge passage of the compressor.

The pistons 11 and 12 are secured to the piston 13 in the following manner: The piston 11 is so formed that it projects downwardly through the piston 12, and the depending portion is fitted into a centrally located depending sleeve 66 integrally formed with the piston 13. The sleeve 66 projects slightly beyond the depending portion of the piston 11 and the pistons 11 and 13 are clamped together by means of a connecting-rod fork 67, which is provided with a screw threaded lug 68, which, by being screwed into the lower end of the depending piston 11, draws the piston 12 firmly against the projection 23 of the piston 13. The prongs 69 of the fork 67 sub-tend a connecting rod bearing 70, through which the wrist pin 71 of the compressor, extends. The end of the connecting rod 6 bears against the bearing 70 and the wrist pin 71 is secured in place by the prongs 69 of the fork 67.

The operation of the apparatus is as follows: During the downward stroke of the compound piston of the compressor, air is drawn into the chamber 7; the air in the annular segregated space of the chamber 7, surrounding the trunk piston 13, is compressed into the chamber 24; and a charge for final compression is delivered from the chamber 24 through the port 26 into the chamber 8. During this stroke of the pis-

ton, the valves 17, 25 and 27 are open and the valve 21 is closed. During the upward stroke of the compound piston, the valve 21 is opened and air is forced from the chamber 7 through the ports 18 into the annular segregated space; and the air confined in the chamber 8 is finally compressed and discharged through the valve 30. The valves 21 and 25 are open during this stroke of the piston, and the valves 17 and 26 are closed. During the upward stroke of the compound piston, the plunger 56 forces fuel past the valve 61 and through the recess 59 into the compressed air discharged from the compressor. The plunger does not operate throughout the entire stroke, owing to the position of the port 53. A relatively small, but the required, amount of liquid fuel is confined in the upper end of the cylinder 52 by the advancing plunger 56 after the port 53 is closed by the plunger, and the fuel is then forced past the valve 61 in the form of a heavy vapor or spray, just as the valve 30 is opening to discharge air from the compressor cylinder 8. I preferably connect the piping 34 with the delivery manifold of an internal combustion engine so that the compressed charge of gas and air is delivered directly to the engine. A portion of the air delivered by the compressor is conveyed through the passage 37, the recess 35 and the piping 36 to the pressure reservoir. With this arrangement, the pressure does not vary materially in the chamber 32, or in the distribution system communicating with it. If, for any reason, the pressure in the chamber 32 decreases a determined amount, the valve 41 will open, in response to the drop in pressure, and will admit air from the reservoir into the exhaust passages of the compressor. With this arrangement, the pressure in the chamber 32 is maintained substantially equal to the pressure in the supply reservoir at all times. Any well known means, for controlling the amount and pressure of the air pumped by the compressor and the amount of fuel delivered by the cylinder 52 and plunger 65; for example, the inlet port 15, may be controlled by a valve automatically actuated by the variations of pressure in the chamber 32; and the flow of fuel, to the cylinder 52, may, in like manner, be varied or completely shut off by the pressure in the chamber 32.

Having thus described my invention, what I claim is:

1. In combination, a compressor casing having a discharge port communicating with a pressure reservoir, a discharge valve for delivering pressure from said compressor to said port and to a distributing chamber, a passage between said port and said distributing chamber and around said valve, and a valve responsive to differences in pressure existing in said chamber and in

the reservoir communicating with said port for controlling the delivery of fluid through said passage.

2. In a compressor, a cylinder having three bores and provided with an inlet port communicating with the largest bore, and a delivery port communicating with the smallest bore, a compound piston for drawing air through the inlet port into the largest bore of the cylinder and for compressing the air through valved ports in the portion of largest diameter of the piston and into an annular space segregated by the piston, a valve carried by the piston for controlling the delivery of air from the portion of largest bore of the cylinder through delivery passages formed within the piston, and a valve carried by the piston for controlling the delivery of air from the piston passage to the portion of smallest bore of the cylinder.

3. A compressor, comprising a cylinder having three bores, a compound piston having three diameters and operating in said

cylinder, and coöperating therewith to form a plurality of compression chambers, an inlet port communicating with one of the chambers so formed and valved passages formed within the piston for establishing communication between said chambers.

4. A compressor comprising a cylinder having three alined bores of different diameter and open at one end, a trunk piston closing the open end of the cylinder and having three portions of different diameter operating in the different bores of the cylinders, and valves mounted on the piston for controlling the delivery of fluid through the piston during the operating of the compressor.

In testimony whereof, I have hereunto subscribed my name this 3rd day of September, 1910.
